AUXILIARY SPARK IGNITION APPARATUS
FOR INTERNAL-COMBUSTION ENGINESIvan Jack Hulbert, London, England, assignor to
Rotax Limited, London, EnglandApplication May 10, 1944, Serial No. 534,923
In Great Britain February 18, 1943

6 Claims. (Cl. 123—148)

This invention has for its object to provide an improved auxiliary spark ignition apparatus for internal combustion engines, the apparatus being of the kind used in conjunction with a magneto for starting an engine and comprising an energising coil adapted to be connected to the primary winding of the magneto, and to be supplied with current from a battery, the coil circuit being controlled by a trembler interrupter.

The invention comprises the combination of an auxiliary energising coil and a trembler interrupter adapted to connect the coil alternately to the battery and to the magneto.

The accompanying diagram illustrates one mode of carrying the invention into effect.

In the diagram *a* indicates a magneto having a primary winding *b* and a secondary winding *c*. Arranged across the primary winding *b* are the usual contact breaker *d* and condenser *e*. The secondary winding *c* is connected to any convenient distributor *f* whereby the high tension discharges are supplied to the sparking plugs *g* of the engine.

In carrying the invention into effect as shown I employ a coil *h* of appropriate size, this coil being provided with an iron core *i*. One end of the coil *h* is adapted to be connected to the earthed end of the primary winding *b* of the magneto *a*. In association with the coil *h* is arranged a trembler interrupter *j* adapted to be actuated by the flux produced in the core *i* when current passes through the coil. The interrupter *j* comprises a pair of insulated vibratory blades *m*, *n* which are arranged parallel with and adjacent to each other, and which at one pair of adjacent ends are anchored to fixed supports *k*, the other ends of the blades being free. The blade *m* carries a pair of contacts *o*, *p* and is connected to the end of the coil *h* remote from that connected to the primary winding *b* of the magneto. The second blade *n* is responsive to the action of the magnetic flux in the core *i* and is extended at one end over the adjacent end of the first blade *m*, the extension being provided with a contact *q*. This latter contact is adapted to co-operate with the contact *p* on the first blade *m*, and to transmit movement to this blade from the second blade *n*. Also the contact *q* is connected to the end of the magneto primary winding *b* remote from that connected to the coil *h*. An adjustably mounted but otherwise fixed contact *r* co-operates with the other contact *o* on the first blade *m*, and is connected to one end of the battery *s*, the other end of the battery being earthed.

With the interrupter in the limit position

shown in the diagram, the contacts *o*, *r* are closed, and current can flow into the coil *h* from the battery *s* and so energise the coil. The subsequent attraction of the second blade *n* by the magnetic flux in the core *i* causes the circuit of the magnetic primary winding *b* to be closed by the contacts *q*, *p* and the circuit of the battery *s* to be opened by the contacts *o*, *r*, whereupon the stored energy of the coil *h* is transferred from the coil to the magneto primary winding where it serves to produce the required spark through the medium of the magneto secondary winding *c*, it being understood of course, that the contact breaker *d* of the magneto primary winding is opened at the appropriate time. On the return of the interrupter to its initial position the cycle is repeated.

By this invention, of which the essential novel feature is the trembler interrupter adapted to connect the coil alternately to the battery and to the magneto, I am able to effect more satisfactory operation of the auxiliary ignition means than with an ordinary trembler interrupter.

Having thus described my invention what I claim as new and desire to secure by Letters Patent is:

1. An auxiliary spark ignition apparatus of the kind specified, comprising the combination of an auxiliary energising coil and a trembler interrupter adapted to connect the coil alternately to the battery and to the magneto.

2. An auxiliary spark ignition apparatus as claimed in claim 1, in which the trembler interrupter comprises in combination a vibratory member adapted to be connected to the coil, a pair of contacts on the vibratory member, a second vibratory member responsive to the flux produced by the coil and adapted to impart movement to the first vibratory member, a third contact provided on the second vibratory member and adapted to co-operate with one of the contacts on the first vibratory member, the third contact being adapted to be connected to the primary winding of the magneto, and a stationary contact adapted to co-operate with the other contact on the first vibratory member and to be connected to the battery.

3. Auxiliary energizing means for a magneto comprising a coil, means to energize the coil, means to transmit the energy of the coil to the primary winding of a magneto, and means to connect the coil alternately to the energizing means and to said primary winding.

4. Auxiliary energizing means for a magneto comprising a coil and core, means to energize the

coil and core comprising a battery, means to transmit the energy of the coil and core to the primary winding of a magneto, and means operable by the coil and core to connect the coil alternately to the battery and to said primary winding.

5. Auxiliary energizing means for a magneto comprising a coil, means to energize the coil comprising a battery, means to transmit the energy of the coil and core to the primary winding of a 10 magneto, and means to connect the coil alternately to the battery and to said primary winding comprising a trembler interrupter operated by the magnetism of the coil to break the battery circuit and connect said winding to said coil.

5

15

6. Auxiliary energizing means for a magneto comprising a battery, a coil, means to connect the coil in circuit with the battery comprising a spring arm normally tending to close a contact in the battery circuit that directs the battery current through the coil, and means to break the circuit from the battery through the coil and to connect the coil with the primary winding of the magneto comprising a spring arm adapted to be displaced by the flux of the coil and to displace the first said spring arm, said spring arms having contacts that close the circuit from the coil to the magneto when they are so displaced.

IVAN JACK HULBERT.
